UNITED STATES PATENT OFFICE.

OTTO A. HOKANSON, OF WOODSTOCK, ILLINOIS, ASSIGNOR TO WOODSTOCK TYPE-
WRITER COMPANY, OF WOODSTOCK, ILLINOIS, A CORPORATION OF ILLINOIS.

TYPEWRITER.

Application filed October 20, 1924. Serial No. 744,573.

This invention relates especially to mechanism for producing the type action, and has for its object the provision of mechanism which will be noiseless in its operation, 5 which will occupy a minimum amount of space so as to permit the standard number of type bars, and which shall be of improved construction and operation.

The invention is exemplified in the combination and arrangement of parts as shown in the accompanying drawings and described in the following specification, and it is more particularly pointed out in the appended claims.

15 In the drawings—

Fig. 1 is a central horizontal section of a typewriter having one embodiment of the present invention applied thereto.

Fig. 2 is a view similar to Fig. 1, showing 20 one manner of applying the invention to a power-actuated typewriter.

As illustrated in the drawings, the invention is shown as applied to a Woodstock typewriter, but it will be understood that it 25 is applicable to other forms of machines. The numeral 10 designates the base frame, having key levers 11 pivoted at 12 thereon and held in their uppermost position by springs 13 in the usual manner employed in 30 Woodstock machines. A transverse bar 13' extends across the typewriter frame and supports a plurality of sub-levers 14 pivoted at 15 thereon. Each of the sub-levers 14 has a bifurcated arm 16 which engages a pin 35 17 on one of the key levers 11. The upright arm of each of the sub-levers 14 engages a slot 18 in a lever 19 pivoted at 19' on a bar 24 extending transversely of the frame of the machine. The typewriter frame is provided with a top plate 20 mounted for slight 40 sliding adjustment in a front and rear direction. The plate 20 is provided with a rack 21 meshing with a pinion 22 actuated by a worm 23. The worm 23 is controlled 45 by a shaft 24 having a finger-piece 25 thereon and an index 26 at the front of the machine. By rotating the finger-piece 25 the plate 20 can be accurately adjusted forwardly and rearwardly. The platen 27 is 50 mounted on a traveling carriage 28 in the usual manner employed in Woodstock machines. The plate 20 carries a plurality of spaced guideways 27', which form slideways extending in a radial direction from the printing point. A sliding type support 28' 55

is provided with rearwardly extending guides 29, which travel in the slots between the guideways 27'. A cross-bar 30 connects the guides 29 and is provided with a slot 31, which receives a pin 32 carried by the end 60 of a toggle link 33. A cooperating toggle link 34 is pivoted at 35 in a slot 36 formed in a block 37, which connects the plate 20 with the front guide 27'. The links 33 and 34 are pivoted to one another by a pin 38. 65 The lever 19 is provided with a slot 39, which engages a pin 40 on the toggle link 33. When the key lever 11 is depressed the lever 19 will be rotated in a clockwise direction as viewed in Fig. 1, into the position 70 shown in broken lines in that figure. This will cause the toggle 33 34 to be straightened, thus moving the type support 28 rearwardly into the position shown in broken lines. The type will be moved into engagement with the paper on the platen, but the 75 action will be one in which the impression is made by pressure rather than by the arrest of a blow. It will be seen that the impression is made at the time that the type reaches the end of its rearward stroke and that the movement of the type is limited by the extension of the toggle 33, 34. The plate 20 is adjusted so that the type will move the proper amount to give the impression 80 desired. If more sheets of paper are placed on the platen the space between the face of the type and the platen may be increased by rotating the thumb piece 25 to retract the plate 20. The index 26 may be provided 85 with suitable characters to indicate the amount of rotation desirable for sheets of paper of ordinary thickness. A stop screw 41 is provided for limiting the upward movement of the toggle link 34 to arrest the 90 links in their extreme extended position. The slot 31 permits any upward movement of the pin 32 resulting from the action of the lever 19 so that there is no upward pressure on the bars 29. The slot 39 may be 95 made of sufficient length to prevent any upward force on the pin 40 and the two slots 31 and 39 give sufficient play to insure free operation of the toggle mechanism. The plate 20 will be curved to conform to the 100 radial direction of the type bar carriers, and the lower ends of the lever 19 at the sides of the machine and the sub-levers 14 will be shaped to provide the proper cooperation 105 for the various lateral positions of the type 110

carriers. It will be noted that the actuating parts for the type carriers are relatively thin links and that the total lateral space occupied is equal to the thickness of only 5 two of these links. The link 34, the lever 19 and the guides 29 are all in the same plane and the link 33 is in the plane adjacent to that of these parts. The total thickness of the actuating parts is less than that 10 necessary for the type so that the mechanism may be made sufficiently compact to accommodate the usual number of type for the standard keyboard. It is thus necessary to provide only two type for each carrier so 15 that the standard single shift arrangement of the platen may be employed for case shift.

In Fig. 2 I have shown the manner of connecting the type action with power driven 20 mechanism such as that shown in my prior application Serial No. 732,615, filed August 18, 1924. The actuating mechanism for the type carrier is the same as that described in connection with Fig. 1. The sub-lever 42, 25 however, is not connected directly with the key levers but is provided with an actuator 43 pivoted thereto at 44. The actuator 43 is provided with a tooth 45, which registers with a power-driven cylinder 46 having 30 teeth 47 thereon for engaging the tooth 45. A spring 48 normally holds the tooth 45 out of contact with the power cylinder 46, but upon depression of any key lever the corresponding actuated tooth 45 is brought into 35 engagement with the teeth 47. This contact is effected by a tappet 49 pivoted to the key lever 11 at 50. On depression of the key lever 11 the tappet 49 moves the actuator 43 downwardly into engagement with the power cylinder 46, whereupon the actuator 40 is moved forwardly until the contact face 51 thereof strikes a disengaging screw 52 and breaks the connection between the actuator 43 and the power drive 46. The actuator 45 is then returned to its initial position by the spring 48. The forward movement of the actuator 43 produces the same action of the lever 19 and the type carrier 28 as is produced by the key levers 11 in the form of 50 the device previously described. It will be seen that the only effort required on the part of the operator is to depress the key lever against the resistance of its spring 13. The actual force for operating the type carriers 55 is furnished by the power driven roller 46.

A support 54 is carried by the plate 20 adjacent the platen 27, and is provided with inclined guides 55 for receiving a V-shaped projection 56 on type carrier 28 to properly 60 guide the type carrier to printing position.

I claim:

1. In a typewriter, a type carrier, a relatively thin flat guide for said type carrier, a frame having guide slots therein for said 65 guide, a toggle comprising a pair of rela-

tively thin flat links, one of said links being disposed in registration with the plane of said guide while the other of said links is disposed adjacent said guide and said first-mentioned link, and an actuating lever for 70 said toggle, said lever being connected with said second-mentioned link and disposed in the plane of said first-mentioned link and guide.

2. In a typewriting machine, a frame, a 75 platen mounted on said frame for transverse movement relative thereto, said platen being shiftable for changing from one case to another, a type carrier slidably mounted on said frame, and actuating means for said 80 type carrier, the transverse thickness of said actuating means not exceeding the transverse thickness of said type carrier to permit said actuating means to be confined laterally to the space between the planes defining the 85 lateral faces of said type carrier.

3. In a typewriting machine, a supporting frame, a platen mounted for transverse movement relative to said frame and for vertical movement for case shift, a type carrier 90 mounted for horizontal sliding movement on said frame, a relatively thin guide plate extending forwardly from said type carrier, said frame having slots therein for receiving said guide plate, a pivot fixed to said frame, a pair of toggle links pivoted to one another, one of said toggle links having pivotal connection with said fixed pivot while the other of said toggle links has a 95 sliding pivotal connection with said guide, an actuating lever for said toggle links, said actuating lever being disposed in vertical registration with said guide and one of said toggle links while the other of said toggle links lies immediately adjacent said actuating lever guide and its cooperating toggle link.

4. In a typewriting machine, a sliding type carrier, a toggle comprising a pair of links having adjacent ends pivoted together, 110 one of said links having the other end thereof free to move longitudinally of said link and connected with said type carrier for actuating said type carrier, a key lever, power driven means controlled by said key lever for expanding said toggle, and means separate from said key lever for transmitting movement from said power driven means to said toggle.

5. In a typewriting machine, a key lever, 120 a type carrier, a support on which said type carrier is mounted for straight line movement, a toggle link for moving said type carrier upon its support and for limiting the movement thereof, a lever for expanding said toggle, power-actuated means controlled by said key lever for operating said lever, and motion transmitting connection separate from said key lever between said power actuated means and toggle expanding lever.

6. In a typewriting machine, a key lever, a platen, a type carrier, a support on which said type carrier is mounted for sliding movement toward said platen, a toggle carried by said support for actuating said type carrier and for limiting the movement thereof upon said support, means for adjusting said support toward and from said platen, a lever for expanding said toggle, power-actuated means for operating said lever, and means controlled by said key lever but separate therefrom for transmitting motion from said power actuated means to said toggle expanding lever.
- 10 7. In a typewriting machine, a key lever, a platen, a type carrier, a support on which said type carrier is mounted for horizontal sliding movement, a toggle comprising a pair of links connected together at one end thereof and having the opposite ends of the links pivotally connected to said support and type carrier respectively, a stop for limiting the upward movement of said toggle, a lever for expanding said toggle, power-actuated means for operating said lever, and means controlled by said key lever but separate therefrom for transmitting motion from said power actuated means to said toggle expanding lever.
- 15 8. In a typewriting machine, a type carrier mounted for straight-line movement, a pair of toggle links for actuating said type carrier, one of said toggle links having a pin and slot connection with said type carrier at one end of said link to permit movement of said end relative to said type carrier in a direction transverse to the movement of said type carrier, a lever connected with said link, and means for swinging said lever upon its fulcrum for straightening the toggle, formed by said toggle links.
- 20 9. In a typewriting machine, a type carrier mounted for straight-line movement, a toggle comprising a pair of toggle links connected together at adjacent ends and having their opposite ends pivotally connected to a fixed pivot and said type carrier respectively, said toggle being collapsible by movement of the adjacent ends of said links downwardly, an operating lever for said toggle having pivotal connection with one of said links and arranged to straighten said toggle by raising the pivotally connected ends of the links thereof, a sublever for operating said toggle straightening lever, a power drive, a key lever, and an actuator controlled by said key lever for connecting said sublever with said power drive.
- 25 10. In testimony whereof I have signed my name to this specification on this 17th day of October, A. D. 1924.
- 30 OTTO A. HOKANSON.
